UNITED STATES PATENT OFFICE.

JONAS HERRMANN, OF COLUMBUS, OHIO.

WINDOW-CORNICE.

SPECIFICATION forming part of Letters Patent No. 236,028, dated December 28, 1880.

Application filed November 8, 1880. (No model.)

To all whom it may concern:

Be it known that I, JONAS HERRMANN, of Columbus, Franklin county, State of Ohio, have invented a new and useful Improvement 5 in Window-Cornices, of which the following is a specification.

My invention in window-cornices relates to that class which may be adjusted so as to adapt them to fit windows of different widths.

10 In the drawings, Figure 1 is a rear elevation of a window-cornice embodying my improvements, the locking-levers being turned down and the parts locked in one position. Fig. 2 is a top view of Fig. 1, partly in section; and Figs. 3 and 4 sections of Fig. 2 on the dotted lines xx and yy , respectively, looking in the direction of the arrow.

Similar letters of reference indicate corresponding parts.

20 The center-piece or bracket A, of suitable size, shape, and ornamentation, is provided at its rear base portion with a tongued and grooved slide, a , made of thin metal bent at one end and entered into the wood, as shown 25 in Fig. 3, this construction forming a neat and durable base for the cornice, as well as a non-warpageable and effective guide for the sliding pieces B B.

The adjustable pieces B B, of suitable length, 30 have formed on their under edge a tongue and groove, to ride in the tongue and groove of the metal slide a . Upon the faces of the adjustable pieces B B are cut lines of locking-grooves, that also form a measuring-scale, as designated 35 by the figures 1 2 3, &c., Fig. 1, the grooves being arranged at definite distances from each other, as, say, one inch or more.

Fastened to the cleat b , forming the upper guide-bar for the adjustable pieces B B, are 40 two plates, $c c$, which serve as guides for the pieces B B. These plates $c c$ are provided with ears $e e$, upon which are pivoted locking-levers ff , the short ends of said locking-levers being rounded so as to readily enter the slots 45 or locking-grooves in the adjustable pieces

B B. These locking-levers ff also serve as pointers by which to regulate the adjustment of the pieces B B.

When desired to adjust the cornice to a given length—say, for instance, three inches—50 the levers are raised and the adjustable pieces moved along until the numbers $1\frac{1}{2}$ $1\frac{1}{2}$, designating the number of inches and fractions traversed by each piece B B, are directly in line with the pointers. Then the levers ff are 55 pulled down, their short ends enter the slots $1\frac{1}{2}$ $1\frac{1}{2}$, and the parts are securely locked. (See Figs. 2 and 3.)

At the ends I have provided metallic miter-plates gg , with elongated slots h , for the reception of the headed pins or screws i upon the end pieces, C C, this forming a simple adjustable connection and making a finished miter-joint, by which the end pieces may be attached to the cornice-pieces B B. This method of 65 uniting the end pieces permits of their convenient removal and substitution of longer or shorter end pieces whenever desired.

Having thus described my invention, I claim as new and desire to secure by Letters Pat- 70 ent—

1. In an adjustable cornice, the combination, with bracket A and its metallic tongued and grooved slide a , of the adjustable tongued and grooved pieces B B, guiding-plates $c c$, and 75 locking-levers ff , substantially as described.

2. In an adjustable cornice, the adjustable pieces B B, provided with the grooved scale, in combination with the locking-levers ff to enter the grooves of the scale, substantially 80 as described.

3. In an adjustable cornice, the herein-described locking-levers ff , provided with plates $c c$, to carry said levers and also guide the adjustable pieces B B, as shown and described. 85

JONAS HERRMANN.
